Specification for Design.

Patented Sept. 14, 1915.

Application filed July 15, 1913. Serial No. 779,224. Term of patent 14 years.

To all whom it may concern:

Be it known that I, JONATHAN S. GREEN, a citizen of the United States, residing at Pittsburgh, in the county of Allegheny and State of Pennsylvania, have invented a new, original, and ornamental Design for Lamps, of which the following is a specification, reference being had to the accompanying drawing, forming part thereof.

Figure 1 is a side elevation of a lamp made in accordance with my design; Fig. 2 is a top or plan view of the lamp; and Fig. 3 is a front elevation of the lamp.

I claim:

The ornamental design for a lamp as shown.

In testimony whereof, I have hereunto subscribed my name this 10th day of July, 1913.

JNO. S. GREEN.
